UNITED STATES PATENT OFFICE

MAURICE H. HOLLINGSWORTH, OF MIAMI BEACH, FLORIDA

MEANS FOR HANDLING CAULKING COMPOUND AND THE LIKE

Application filed July 11, 1931. Serial No. 550,934.

This invention relates to a means for facilitating the handling of caulking materials, the general object of the invention being to place the caulking material or compound or 5 the like in a tube of suitable material which is so formed that a part of the tube can be readily separated from another part so that by removing a part of the tube, a portion of the compound will be exposed and can be 10 applied to the surface or article to be caulked very easily and without coming in contact with the hands of the user.

This invention also consists in certain other features of construction and in the 15 combination and arrangement of the several parts, to be hereinafter fully described, illustrated in the accompanying drawing, and specifically pointed out in the appended claim.

20 In describing the invention in detail, reference will be had to the accompanying drawing wherein like characters denote like or corresponding parts throughout the several views, and in which:—

25 Figure 1 is a view showing one manner of carrying out the invention.

Fig. 2 is a view partly in section looking toward the side of the tube with the compound therein, and with the perforations at 30 the top and bottom.

Fig. 3 is a cross sectional view through the tube with the compound therein.

Fig. 4 is a view showing a portion of the top section of the tube removed from the 35 compound and the lower portion entirely removed.

Fig. 5 is a view showing a portion of the lower portion of the tube removed, with the upper section still in place.

40 As shown in these views, the caulking compound 1 is placed in a tube 2 of paper or any other suitable material and the tube is formed in two sections by the lines of perforations 3.

45 Thus when the tube is to be used, a por-

tion of one section is removed as shown in Fig. 5, so that a part of the compound can be placed against the surface or article and a part of the other section of the tube used to press the compound in place.

50 As the work proceeds, the lower section is pulled to a greater extent from the compound so other portions of the compound can be placed against the surface, and then after the work is complete, the top section 55 can be removed as shown in Fig. 4.

While the invention is mainly designed for caulking compounds, it will of course be understood that it can be used with any other viscous plastic substances and while the 60 drawing shows the tube of circular form, it will of course be understood that the tube may be of any desired shape, and the lines of perforations can also be placed wherever desired.

65 The tubes may be compacted in a bucket or pail until used and a volume of compound may be placed in a pail presumably equal to the volume of compound placed in a bucket in the bulk form. In using the 70 tube it is cut the length of the surface upon which it is desired to place the compound.

The tube is placed upon the surface so that a line passing through the perforations would pass through the center of each side of 75 the tube and would be parallel with the surface upon which the caulking compound was being applied. The paper at the lower half of the circle is torn at the perforations for a fraction of an inch and is pulled under 80 the tube toward the bottom of the tube.

85 It is presumed that the operator will apply the strip of compound to the surface from the top to the bottom as would be illustrated in a plan or elevational view, although the compound could be applied from the bottom toward the top. The operator places his finger on the paper covering the top half of the tube and by pressure forces the exposed caulking compound upon 90

the surface that is to be covered by the compound. The caulking compound firmly adheres to the surface. As the paper below the perforations is torn at the perforations 5 and pulling under the tube toward the bottom of the tube, pressure is applied to the paper covering the top half of the compound. At any time during this process or at the end of this process, the paper covering the 10 top half of the caulking compound may be pulled away from the caulking compound leaving an even and exactly uniform layer of compound in the exact position where it is desired to have the compound.

15 This process practically entirely eliminates the necessity of the fingers or hands coming in contact with the compound and generally will eliminate the necessity of a knife or other tool touching the compound. In addition to many pronounced advantages, much labor is saved. One method used by those 20 who use caulking compound is to roll an amount of whiting, chalk or other substance into the compound so that it can be handled as the old fashioned putty can be handled and another method is to coat the hands with oil and to roll oil into the compound. 25 These methods greatly reduce the value of the compound and reduce the desirable and 30 essential properties.

For caulking around door and window sills or filling external cracks where the compound will not be protected by a frame or with glass, the compound will harden and 35 the undesirable deterioration process will in time deteriorate the compound. If desired, the paper covering the upper half of the compound may not be removed but may be pressed firmly into the compound. The 40 paper will protect the layer of compound from the atmospheric deterioration. The inner surfaces of the tube may be impregnated with oil or otherwise treated so that it will not offer an undesirable resistance in 45 being removed from the compound.

When it is desired to not remove the top half of the paper tube it is conceivable that the upper half of the paper tube would not be treated in any way to reduce the adhesion 50 of the compound and if treated in any way it would be treated so as to increase the adhesion of the compound. When the upper half of the paper tube would not be removed it is advisable that the outside of 55 the paper be waterproofed, painted or otherwise treated so as to reduce the deterioration of the paper and to increase its protecting properties.

Several sizes of caulking compound will 60 meet the standard requirements for the use of caulking compound. It is self-evident that if a wide ribbon of compound is desired, the desired width of compound can be built up by a series of parallel strips of 65 compound placed close together.

It is thought from the foregoing description that the advantages and novel features of the invention will be readily apparent.

It is to be understood that changes may be made in the construction and in the combination and arrangement of the several parts, provided that such changes fall within the scope of the appended claim.

Having thus described my invention, what I claim as new is:

An article of manufacture comprising an elongated strip of caulking material or the like, an elongated tubular cover for the strip, formed of flexible material, said cover having a pair of weakened lines extending longitudinally from one end to the other therein, said lines being substantially opposite each other and dividing the cover into two sections whereby a portion of one section can be removed and a portion of the other section used to press said material against a surface the latter section also acting as a protective covering for the strip of caulking material when said strip of caulking material is in operative position.

In testimony whereof I affix my signature.

MAURICE H. HOLLINGSWORTH.
